UNITED STATES PATENT OFFICE.

HANS HOLZWARTH, OF HAMILTON, OHIO, ASSIGNOR TO THE HOOVEN-OWENS-RENTSCHLER COMPANY, OF HAMILTON, OHIO, A CORPORATION OF OHIO.

GOVERNING MECHANISM FOR FLUID-ACTUATED MOTORS.

SPECIFICATION forming part of Letters Patent No. 746,836, dated December 15, 1903.

Application filed October 22, 1903. Serial No. 178,063. (No model.)

To all whom it may concern:

Be it known that I, HANS HOLZWARTH, a citizen of Germany, residing at Hamilton, county of Butler, and State of Ohio, have invented new and useful Improvements in Governing Mechanism for Fluid-Actuated Motors, of which the following is a specification.

My invention relates to improvements in governing mechanism for fluid-actuated motors.

The object of my invention is to provide adequate means for regulating the supply of motive fluid to the motor, whereby the speed of the latter may be kept uniform, the invention being especially designed for the control of turbines.

In the following description reference is had to the accompanying drawings, in which—

Figure 1 is a vertical sectional view of my invention drawn on line *x x* of Fig. 2. Fig. 2 is a plan view with the upper portion of the casing removed. Fig. 3 is a detail sectional view drawn on line *y y* of Fig. 2. Fig. 4 is a detail sectional view drawn on line *t t* of Fig. 2.

Like parts are identified by the same reference characters throughout the several views.

1 is a turbine-shaft or a reduced end thereof. 2 represents governing-weights having levers 3 pivoted to a shaft-collar at 4.

5 is a sleeve splined to the shaft and longitudinally movable thereon. This sleeve is connected with the governing-weights by links 6.

35 A valve-actuating shaft 8 is arranged to communicate motion through the bevel-gears 9 and 10 and valve-stem 11 to operate a valve at 12, controlling the delivery of motive fluid to the turbine through the pipes 13 and 14.

40 The valve-actuating shaft 8 is driven from the turbine-shaft 1 through the medium of a worm-gear 18, worm-wheel 19, tubular shaft 20, sliding shaft 21, extending through the shaft 20 and splined thereto, friction-wheel 22

45 on the shaft 21, and a friction-wheel 23 and its supporting-sleeve 24, the latter being mounted on and splined to the valve-actuating shaft 8. The movement and direction of rotation of said shaft 8 is determined by the relative positions of the friction-wheels 23 with

reference to the center of the friction-wheel 22, and the sleeve 24 is movable longitudinally along the shaft 8 for this purpose. The movement of the shaft 8 is also controlled by moving the friction-wheel 22 into and out of 55 contact with the friction-wheel 23 by adjusting the shaft 21 axially in the tubular shaft 20. Both the movements of the friction-wheel 23 axially of shaft 8 and of the friction-wheel 22 axially of the shaft 20 are controlled by 60 the governor.

The friction-wheel 22 is normally held out of contact with the frictional wheel 23 through the medium of a spring-controlled bell-crank lever 28, fulcrumed at 29 and having one 65 forked arm *a* loosely engaging studs 30, projecting from a collar 31, loose on the shaft 21. The bell-crank lever 28 is actuated (against the tension of its controlling-spring 35) from the sleeve 5 through the medium of studs 37, 70 antifriction-rollers 38, mounted thereon, a yoke 39, mounted on the rollers, and a post 40, connected with the yoke, the latter being linked to an arm *b* of said bell-crank lever 28. The arms of the yoke 39 are provided with 75 V-shaped notches 41, in which the antifriction-rollers 38 are engaged, whereby movement of the sleeve 5 in either direction from its normal position will be transmitted to actuate the yoke and post to push the same 80 outwardly at right angles to the sleeve and shift the friction-wheel 22 into contact with wheel 23 through the medium of the bell-crank connections above described. The normal position of contact between the friction-wheels 23 and 22 is at the center of the latter. A bell-crank lever 45 is used to shift the hub 24 and wheel 23 along the valve-actuating shaft 8, so that wheel 23 will be moved to one side or the other of friction-wheel 22 85 in accordance with the direction in which it is desired to actuate the valve. This movement is also controlled by the governor, the bell-crank lever 45 having yoke-arms *d*, loosely engaging the studs 37, and other yoke-arms 90 *e*, having links *f* engaging studs 46 on a collar 47, rotatably mounted on hub 24. The pivot-rod 49 of the bell-crank lever 45 is suitably mounted in bearing-brackets 50, connected 95 with the casing.

The operation of the device is as follows: When the turbine is at normal speed, the parts are in the position in which they are shown in the drawings. Any increase of speed causes the governing-weights and sleeve 5 to move outwardly, thus shifting the friction-wheel 23 inwardly through the medium of the bell-crank 45 and also forcing the friction-wheel 22 into contact with wheel 23 through the medium of the bell-crank 28 and its connections. The movement of the friction-wheel 23 will then be communicated to operate the valve-actuating shaft 8 and close the valve at 12 until the decreased speed of shaft 1 permits the governing-weights and connections to reassume their normal position. When the speed of shaft 2 is too slow the governing-weights move inwardly, when friction-wheel 23 is shifted outwardly to the opposite side of the center of friction-wheel 22 and the latter brought in contact with it to open the valve at 12. The friction-wheels and driving-gearing may be arranged to actuate the valve at any desired speed.

Having thus described my invention, what I claim as new, and desire to secure by Letters Patent, is—

1. The combination with the shaft of a fluid-driven motor; of a valve-actuating wheel; a driving-wheel therefor shiftable into and out of operative relation thereto; a centrifugal governor operatively connected with the shaft; connections controlled by the governor for shifting one of wheels past the axial line of the other; and connections also controlled by the governor for shifting said wheels into and out of contact with each other.

2. The combination with the shaft of a fluid-driven motor; of a valve-actuating friction-wheel; a friction driving-wheel at right angles thereto and movable into and out of operative relation thereto; connections for actuating the driving-wheel from the shaft; a centrifugal governor operatively connected with the shaft; a shifting-lever for the

driving-wheel; a shifting-lever for the valve-actuating wheel; and connections adapted to communicate motion from the governor to said levers.

3. The combination with the shaft of a fluid-driven motor; of a valve-actuating friction-wheel; a friction-driven wheel mounted for side contact therewith, and operatively connected with the shaft; axially-movable supports for said wheels; centrifugal governing-weights operatively connected with the shaft; an axially-movable sleeve linked to the governing-weights; and motion-transmitting connections between the sleeve and said friction-wheel supports. 60

4. The combination with the shaft of a fluid-driven motor; of a valve-actuating friction-wheel; a friction driving-wheel mounted for side contact therewith; axially-movable supports for said wheels; lever connections 65 arranged to support said driving-wheel normally out of contact with the valve-actuating wheel; a governing device in operative relation to said shaft; an axially-movable sleeve mounted on said shaft, and linked to 70 the governing device; and a yoke having angular faces, adapted to be engaged by projections on said sleeve when the latter is moved in either direction from normal position; said yoke being arranged to transmit 75 motion through said lever connections to move the driving friction-wheel into contact with the valve-actuating wheel; together with means for transmitting motion from the sleeve to shift the valve-actuating wheel to 80 opposite sides of the axis of said driving-wheel in accordance with the speed of the governor.

In testimony whereof I affix my signature in the presence of two witnesses.

HANS HOLZWARTH.
